LATCHABLE ELECTROMAGNETIC
CONTACTOR

Delbert Ellis and James H. Alspach, Wilkinsburg,
Pa., assignors to Westinghouse Electric Corporation,
East Pittsburgh, Pa., a corporation of
Pennsylvania

Application December 8, 1943, Serial No. 513,363

11 Claims. (Cl. 200—87)

Our invention relates to electromagnetic contactors such as relays, overload switches, motor starters and the like devices.

It is an object of the invention to provide a contactor of this type that can be actuated manually and independently of the operating condition of the electromagnet, for instance, in the event of failure of the electromagnetic actuating means.

Another object of our invention is the provision of a contactor that can be safely latched in its circuit opening or closing position, for instance, when operating conditions are expected to involve high impact shocks or vibrations under which a magnetic contactor might perform uncontrolled and undesired operations, as may be the case on board war ships.

A further object of our invention is to devise a contactor which is provided with latch means which are capable of latching the contactor in its "on" or "off" position during periods of shocks or vibrations in order to thus prevent uncontrolled operation, while also permitting an actuation of the contactor, subject to control by the attendant, during periods of persistent shock or vibration so that the latch means can be released at will within such periods.

It is also an object, in conjunction with the foregoing, to devise a magnetically and manually actuatable contactor, such as a motor starter, which requires extremely little space and a minimum of movable parts, especially for the manual control portion. More particularly, we aim at providing a contactor of the type mentioned by merely adding a manual control and latch unit of small compass to an otherwise complete and operative electromagnetic relay of customary design, thus obtaining a simple and inexpensive dual actuation in accordance with any of the aforementioned objects.

The invention is exemplified by the embodiment of an electromagnetic contactor, applicable as a motor starter, which is shown in the drawing by a part sectional side view in Fig. 1, a part sectional front view in Fig. 2, the manual control portion being removed in the showing of Fig. 1 and separately illustrated by a front view in Fig. 3, a cross section in Fig. 4, and an illustration of two appertaining latch levers in Figs. 5 and 6.

Referring to Figs. 1 and 2, a plate 1 forming the mounting base of the individual contactor parts carries a magnet frame 2 with a solenoid coil 3. A guiding structure 4 traverses the axial bore of coil 3 and accommodates a plunger type magnet core or armature 5 so as to permit the

core a sliding vertical motion within the coil 3. A holding plate 6 is firmly attached to the core 5. An insulating body 7 is secured to the plate 6 by means of two brackets 8 and 9. Four movable contacts are mounted on the insulating body 7, each consisting of a saddle member such as the one denoted by 10, a contact 11 slidably held by the saddle member, and a contact spring 12 straddled by a saddle member and tending to move the contact 11 away from body 7 in order to establish the desired contact pressure when the contact engagement is closed. Four corresponding stationary contacts, such as the one denoted in Fig. 1 by 13, are mounted on an insulating body 14 firmly attached to the base plate 1. In the illustrated position of the contactor, the movable contact and core assembly is in the lower position so that its contacts 11 are separated from the respective stationary contacts 13. When the magnet coil 3 is energized, the core 5 is lifted so that the contact assembly is raised and an electric contact established between each pair of contacts 11 and 13. This contact engagement exists as long as the magnet coil remains energized and is interrupted upon deenergization of the coil by the downward motion of the movable assembly due to its gravity.

The magnet frame 2 forms two lugs 35 which according to Fig. 1 extend in a common plane at 30 the front side of the contactor. A manual control and latching unit contained in a casing 15 is firmly secured to the lugs 35 by means of screws 36 as is apparent from Fig. 2. The design of this unit will be understood from Fig. 2 in conjunction with Figs. 3 through 6 to which reference is had in the following.

The casing 15 is traversed by a pin 16 which extends in parallel to the surface plane of the base plate 1 and lies close to the bottom portion 40 of the casing 15. Two actuating levers 17 and 18 are fulcrumed by pin 16. A control lever 19 also fulcrumed on pin 16 is located between levers 17 and 18, the necessary spacing between the casing and the individual levers being maintained 45 by spacing washers 20, 21, and 22. The control lever 19 comprises a substantially U-shaped spring whose two arms 23 and 24 are resilient in the plane of illustration in Fig. 4 and have the tendency to spread apart so as to assume the position shown in this figure. Two insulating finger portions 25 and 26 are mounted on the ends of arms 23 and 24, respectively.

The casing 15 has a raised or bulging portion provided with a slot 27 for the passage of arms 55 23 and 24 of the control lever 19. The lateral

edges of the slot 27 form three pairs of notches located at 28, 29 and midway between the locations 28 and 29 (Fig. 3). Due to the resiliency of the lever arms 23 and 24, these arms will catch into corresponding pairs of notches when the control lever is in the corresponding position.

The lever 17 according to Figs. 2, 4, and 5 has an angularly projecting nose 30 for engagement by the lever arm 23, and forms a latch or cam portion at 31 for cooperation with the movable contact assembly of the contactor. The lever 18 has an angularly projecting nose 32 for cooperation with the arm 24 of the control lever 19 and forms a cam or latch portion at 33 for coaction with the movable contact assembly.

When the control lever is in the mid-position, as shown in Figs. 2, 3, and 4, the lever 17 is disengaged from the contact assembly while the cam portion 33 of the lever 18 lies underneath a shoulder 34 formed by the magnet core (Figs. 1 and 2). In this mid-position, the manual control unit is inoperative and permits a free operation of the electromagnetic actuating device. That is, when the core 3 is energized and lifts the movable assembly, the shoulder 34 is free to move away from the lever portion 33.

In order to actuate or latch the contactor manually, the two handle portions 25 and 26 are pressed together by the attendant, thereby releasing the arms 23 and 24 from the rests formed by the central pair of notches, so that the lever 19 can be moved into its upward or downward position. Moving the control lever downward toward its "in" position causes the arm 24 to abut against the nose 32 and to entrain the lever 18, thereby turning its cam portion 33 in the counterclockwise direction. If the contactor was in the circuit interrupting position shown in Figs. 1 and 2, the lever portion 33 abuts against the shoulder 34 and hence moves the contact assembly upwardly into contact closing position. When the control lever reaches its lowermost position, the arms 23 and 24 will spring into the rests formed by the pair of notches 29 so that the control lever is safely latched in the interrupting position of the contactor. If the contactor was in the circuit closing position before moving the control lever into the "in" position, this motion has merely the effect of latching the contactor in the circuit closing position.

Starting again from the inoperative mid-position of the control lever, the movement of this lever to the uppermost or "out" position determined by the pair of notches 28 will cause the lever arm 23 to entrain the nose 30 of lever 17, thereby moving the latch portion 31 into the path of the movable contact assembly. Assuming that the contactor was in the illustrated circuit opening position, the lever portion 31 will reach a position close to the upper end of the bracket 9 (Fig. 2). Hence, upon latching of the control lever in the "out" position, the lever 17 will prevent the movable contact assembly from being attracted by the magnet. If the magnet coil was energized before moving the control lever into the "out" position, the lever portion 31 engages the bracket 9 in an earlier part of the lever motion and will then entrain the movable contact assembly into the interrupting position against the force of the electromagnetic device.

It will be seen from the foregoing description that a contactor according to our invention permits a manual operation under control by the attendant and irrespective of the operating condition of the electromagnetic control device. Hence,

this contactor can be actuated in the case of failure of the electromagnetic device or its current supply, or under conditions which render it desirable to operate the contactor at times or under conditions not intended for automatic actuation. It will also be understood from the foregoing that when the contactor is used under conditions where high impact, shocks, or vibrations are to be expected, the contacts may be locked at will either in the closing or opening position so that shocks cannot cause uncontrolled operations.

A contactor as described in the foregoing has also the advantage that the manually operable actuating and latch means are designed as a unit which can be attached to an otherwise complete and operative electromagnetic switch or relay. This permits using the same or a similar relay design with or without the manual control unit depending upon the particular purpose of the apparatus. The above described example shows further that the manual actuating and latching mechanism is of extremely simple design and function and requires very little space as compared with the dimensions of customary contactors.

While we have exemplified the invention by an embodiment showing a solenoid type magnetic device with a rectilinear motion of its movable assembly, it will be obvious to those skilled in the art that the invention can also be applied to contactors of other design and type, and that various modifications and changes in design can be made without departing from the essential features of our invention. We, therefore, wish this specification to be understood as illustrative rather than in a limiting sense.

We claim as our invention:

1. An electric contactor having contact means movable between two contact positions and biased toward one of them, electromagnetic actuating means for moving said contact means into its other contact position, manual means arranged for moving said contact means between said contact positions independently of said electromagnetic means, said manual means having three operating positions and engaging said contact means in two of said three operating positions while being disengaged therefrom in said third operating position, and manually releasable means for locking said manual actuating means in any of said three operating positions.

2. An electric contactor having contact means movable between two contact positions and biased toward one of them, electromagnetic actuating means for moving said contact means into its other contact position, and movable latch means having three latching positions and being disengaged from said contact means when placed in one of said positions in order to then permit the operation of said electromagnetic means, said latch means being arranged to engage said contact means when moved out of said one position to latch said contact means in said contact positions respectively.

3. An electric contactor having contact means movable between two contact positions and biased toward one of them, electromagnetic actuating means for moving said contact means into its other contact position, and operator-actuable latch means having three latching positions and being disposed for selectively latching said contact means in either of said contact positions thereby rendering said electromagnetic means ineffective when said latch means are placed in two of said latching positions respectively, said

remaining latching position being provided for unlatching said contact means to render said electromagnetic means operative.

4. An electric contact having contact means movable between two contact positions and biased toward one of them, electromagnetic actuating means for moving said contact means into its other contact position, and operator-actuable latch means movable between two operative and one inoperative positions, said latch means engaging said contact means in said operative positions to hold it in its contact positions respectively while being disengaged in said inoperative position, and manually releasable means for locking said latch means in any of its three positions.

5. An electric contactor having a contact controlling member movable between different contact positions, electromagnetic means for actuating said member, normally inoperative latch means for locking said member in said positions, a manual control movable between inoperative and operative positions for actuating said member independently of said electromagnetic means, said control being disposed for engaging and actuating said latch means respectively when moved from said inoperative to an operative position, and manually releasable latch means forming part of said control for securing the latter in any of its selected positions.

6. An electric contactor having a contact controlling member movable between two contact positions, electromagnetic means for actuating said member, two independently movable actuating elements disposed for engaging and moving said member in opposite directions respectively and being normally out of engagement therewith, a movable manual control having two operative positions and an intermediate inoperative position for entraining said elements respectively when displaced from its inoperative position so as to move said member independently of said electromagnetic means, and spring biased latch means associated with said control for securing it in any of its three positions.

7. An electric contactor having a contact controlling member movable between two contact positions, electromagnetic means for actuating said member, two independently rotatable actuating levers disposed for engaging and moving said member in opposite directions respectively and being normally out of engagement therewith, a control lever having two operative positions and an intermediate inoperative position, said control lever being disposed for entraining said actuating levers respectively when displaced from its inoperative position so as to move said member independently of said electromagnetic means, and a stationary structure forming rests adjacent to the path of said control lever for securing it in any of its three positions.

8. An electric contactor having a contact controlling member movable between two contact positions, electromagnetic means for actuating said member, two independently rotatable actu-

ating levers disposed for engaging and moving said member in opposite directions respectively and being normally out of engagement therewith, a control lever having two operative positions and an intermediate inoperative position, said control lever having a common fulcrum axis with said actuating levers and being disposed for entraining said actuating levers respectively when displaced from its inoperative position so as to move said member independently of said electromagnetic means, and a stationary structure forming rests adjacent to the path of said control lever, and said control lever being resilient so as to snap into said rests in any of its three positions.

9. An electric contactor having a contact controlling member movable between two contact positions, electromagnetic means for actuating said member, two independently rotatable actuating levers disposed for engaging and moving said member in opposite directions respectively and being normally out of engagement therewith, a control lever having two operative positions and an intermediate inoperative position, 20 said control lever having two resilient arms for entraining said actuating levers respectively when displaced from its inoperative position so as to move said member independently of said electromagnetic means, and a stationary structure 25 forming rests adjacent to the path of said control lever on both sides thereof for engagement by said two arms respectively in order to move said control lever in any of its three positions while releasing said control lever upon manual compression of said arms toward each other.

10. An electric contactor having contact means movable between contact opening and contact closing positions and biased toward one of said positions, electromagnetic actuating means for moving said contact means into said other position, latch means for locking said contact means selectively in either of said positions to prevent uncontrolled operation of said contact means, operator-controllable release means for unlocking said latch means, and operator-controlled means for actuating said contact means upon release of said latch means.

11. An electric contactor having contact means movable between contact opening and contact closing positions and biased toward one of said positions, electromagnetic actuating means for moving said contact means into its other contact position, latch means for locking said contact means in either of said positions to prevent uncontrolled operation of said contact means during periods of shock, operator-controllable release means for unlocking said latch means in order to permit controlled operation during such periods, and manual means forming part of said 55 release means for actuating said contact means independent of the operation of said electromagnetic means.
